ARMORED AMPHIBIOUS COMBAT VEHICLE

Roger L. Gamaunt, Los Altos Hills, Calif., assignor to
Lockheed Aircraft Corporation, Burbank, Calif.

Filed Sept. 26, 1968, Ser. No. 13,717

Term of patent 14 years

Int. Cl. D12—13

U.S. Cl. D14—3

Fig. 1

FIG. 2

FIG. 3

FIG. 4

FIG. 5

FIG. 6

FIGURE 1 is a perspective view of an armored amphibious combat vehicle showing my new design,

FIGURE 2 is a side elevational view thereof,

FIGURE 3 is a front elevational view thereof,

FIGURE 4 is a top plan view thereof,

FIGURE 5 is a rear elevational view,

FIGURE 6 is a perspective view of the rear and side.

The dominant features of my design as disclosed reside in the parts shown by means of full lines in the drawings.

I claim:

The ornamental design for an armored amphibious combat vehicle, as shown and described.
